UNITED STATES PATENT OFFICE.

WILLIAM J. GUERIN, OF BROOKLYN, NEW YORK.

ICE-CREAM-DISPENSING MACHINE.

1,422,198.

Specification of Letters Patent. Patented July 11, 1922.

Application filed December 6, 1921. Serial No. 520,219.

To all whom it may concern:

Be it known that I, WILLIAM J. GUERIN, a citizen of the United States, residing at Brooklyn, in the county of Kings and State 5 of New York, have invented new and useful Improvements in Ice-Cream-Dispensing Machines, of which the following is a specification.

This invention relates essentially to an ice-10 cream dispensing or distributing machine in which the transverse sides of a paste board box made to contain the cream gauges the quantity forced from a can or tank.

An object of the invention is to provide 15 a can with a slidable tubular plunger carrying a pair of slides the movements of which are controlled by the downward pressure of the box inverted over the plunger.

Another object of the invention is to provide 20 means actuated by the operator for sliding the plunger downward into the can so that a predetermined quantity of the cream will be forced into the inverted box.

The novel combinations of the invention 25 are more fully described in the following specification and claims reference being made to the accompanying drawings in which:

Figure 1 represents a vertical section 30 taken along the line 1-1 of Figure 3 and showing the can placed in a refrigerator.

Figure 2 is a vertical section of the plunger taken along the lines 2-2 of Figure 3.

Figure 3 is a plan view partly in section 35 of the same.

Figure 4 is a similar view showing the slides open.

Figure 5 is a detail view of the plunger 40 actuating mechanism.

Figure 6 is a plan view of an inclined block.

Figure 7 is a vertical section taken along the line 7-7 of Figure 4 on a smaller scale.

In the drawings the numeral 10 designates 45 a can or tank containing the usual number of gallons of ice-cream and having a funnel shaped bottom 11 the function of which will be hereinafter described. The can is arranged in a refrigerator 12 having the usual opening 13 at the top normally closed by a cover 14 to give access to the can.

The top of the can is closed by a slidable, 50 tubular plunger 15 having a packing ring 16 to give a tight fit and prevent any of

the cream from being squeezed between the wall of the plunger and the can. In the interior of the plunger is located a truncated conical compartment 17 with a rectangular opening 18 for the ejection of the cream. 60 When the plunger is in its lowest position in the can the truncated compartment telescopes over the funnel to substantially force all the cream from the can.

The opening leading to the compartment 65 is normally closed by a pair of slides 19 having a series of rollers 20 made to glide on tracks 21 fixed to the top of the plunger. The slides are moved to their closed position by the expansion of coiled springs 22 one 70 coacting with the side of each slide. Each slide also carries an angular track 24, one being opposite the other. A pair of blocks with inclined faces 25 to form a V or a wedge shaped opening are mounted to move by 75 means of rollers 26 along the angular tracks. The blocks have triangular sides so that they will conform to the angular tracks.

The means for actuating the inclined blocks includes a cardboard inverted box 80 27 positioned by an operator to engage the faces of the blocks. The box is inclosed in a holder or casing 28 to prevent it from being crushed. The top or mouth of the casing and the box rides down the inclined 85 planes when pushed from above thus sliding the blocks away from each other along the angular tracks to spread them and open the slides. The movement of the two slides is at right-angles to the movement of the 90 blocks and at reverse directions with each other. The limit of the movement of both inclined blocks is governed by the transverse dimensions of the box. For example, a small box for holding a gill of cream will 95 initially be supported at a narrower part or nearer the vertex of the V when the blocks are together so that when it is pushed down it accordingly moves the blocks and slides uncovering an opening corresponding 100 to the size of the mouth of the box.

A knife 30 for cutting the cream after it is forced into the box is mounted at the upper part of the conical compartment. The knife is connected to cords 31 extending forwardly as indicated in Figure 4. The cords are guided by rollers 32 and a knob 33 on the upper portion of the plunger is made to be pulled upward to move the knife in a rectilinear path over the opening. Springs 110

34 connected to the back of the knife will pull it back out of action when the knob is released.

The mechanism for forcing the plunger into the can consists of a pair of standards 35 secured to the plunger and projecting upwardly. A series of blocks 36 each having a stud or roller 37 are connected to the standards. Links 38 are employed to couple 10 the blocks together and springs 39 permit a small degree of flexibility but holds them practically in a vertical position. When the plunger is in its upper position the blocks that are out of action are partly housed or 15 guided in tubes 40 secured to the upper part of the refrigerator. A step by step movement is transmitted to the blocks on each side to force the plunger into the can by means of a pair of levers 41 projecting from the top 20 of the refrigerator. The levers can be connected together so that both will be operated simultaneously. Each lever is supported by means of antifriction rollers 42 on tracks 43 suspended from the top of the refrigerator. A spring 44 restores the levers to the 25 position shown in Figure 5 and a cam 45 is adapted to actuate a spring latch 46 by pushing the levers. The spring latch carries an oscillating detent 47 held in action 30 to engage a stud roller on one of the blocks by a spring 48 connected to the tail of the detent and casing of the latch.

It will be seen that when the cam is pushed it will move the latch and the detent 35 with the stud downward thus forcing the plunger further into the can. When the latch is released the detent swings out of engagement with the stud until it reaches the end of its stroke where it snaps back into 40 engagement with the succeeding stud. The downward movement of the plunger causes the cream in the can to be ejected from the opening in the plunger packing it into the inverted box as indicated in Figure 7 and 45 the lower end can then be cut by the actuation of the knife. The springs for closing the slides also exert a lateral push to the inclined blocks thereby retrograding them to their initial positions.

50 I claim:

1. In a dispensing machine the combination with a plunger having an opening, of slides arranged to normally close the opening, and means controlled by a container 55 for actuating the slides.

2. In a dispensing machine the combination with a plunger having an opening, of slides arranged to normally close the opening, and means controlled by the mouth of 60 a container for actuating the slides.

3. In a dispensing machine the combina-

tion with a tubular plunger having an opening, of slides arranged to normally close the opening, and means controlled by the mouth of a container for actuating the slides. 65

4. In a dispensing machine the combination with a tubular plunger having an opening at the top, of slides arranged to normally close the opening, and means controlled by the mouth of a container for actuating the 70 slides.

5. In a dispensing machine the combination with a tubular plunger having a truncated conical compartment provided with an opening at the top, of slides arranged to 75 normally close the opening, and means controlled by the mouth of a container for actuating the slides.

6. In a dispensing machine the combination with a tubular plunger having a truncated conical compartment provided with an opening at the top, of slides arranged to normally close the opening, and inclined plane members controlled by the mouth of 80 a container for actuating the slides. 85

7. In a dispensing machine the combination with a can, of a tubular plunger having a truncated conical compartment with an opening at the top sliding in the can, slides arranged to normally close the opening, inclined plane members controlled by the mouth of a container for actuating the slides, and means for forcing the plunger 90 into the can.

8. In a dispensing machine the combination with a can, of a tubular plunger having a truncated conical compartment with an opening at the top sliding in the can, slides arranged to normally close the opening, inclined plane members controlled by the mouth of a container for actuating the slides, means for forcing the plunger into the can, and a knife carried by the plunger. 95

9. In a dispensing machine the combination with a can, of a tubular plunger having a truncated conical compartment with an opening at the top sliding in the can, slides arranged to normally close the opening, inclined plane members controlled by the mouth of a container for actuating the slides 100 to move at right angles to the members, means for forcing the plunger a predetermined distance into the can, and a knife carried by the plunger. 105

In testimony whereof I have hereunto set 115 my hand in the presence of two subscribing witnesses.

WILLIAM J. GUERIN.
